UNITED STATES PATENT OFFICE.

LEWIS S. DANIELS, OF FOXBOROUGH, MASSACHUSETTS.

DESIGN FOR A RADIATOR FOR A STEAM-HEATER.

Specification forming part of Design No. 5,735, dated April 2, 1872.

Specification describing a Design for Radiators, invented by LEWIS S. DANIELS, of Foxborough, in the county of Norfolk and State of Massachusetts.

My design consists in ribbing the columns of a radiator with a series of ribs extending nearly half around the pipe, these horizontal ribs being bisected by a vertical rib, the ends of the ribs being joined by arcs, so as to give the effect of a sinuous line. Between this sinuous line a vertical rib is located. The vertical bisecting rib is so placed that it coincides with the parting line in the mold. The vertical ribs between the sinuous ribs are so lo-

cated as to occupy a position at the lowest and highest point in the mold, so that they may draw. The sinuous ribs, being nearly in the same position, will also draw without difficulty.

This description will be best understood by inspection of the accompanying print.

What I claim as my invention is—

A design for a radiator, in which the surface is ribbed, substantially as described and shown.

LEWIS S. DANIELS.
